US0D1103274S

(12) **United States Design Patent** (10) **Patent No.:** **US D1,103,274 S**
(45) **Date of Patent:** **** Nov. 25, 2025**

(54) **INTERACTIVE PHONICS BOARD SET**

(71) Applicant: **Rocking Chair Readers, LLC**, Austin, TX (US)

(72) Inventor: **Jennifer Renee Kasino Dezelle**, Round Rock, TX (US)

(73) Assignee: **Rocking Chair Readers, LLC**, Austin, TX (US)

(**) Term: **15 Years**

(21) Appl. No.: **29/872,549**

(22) Filed: **Mar. 14, 2023**

Related U.S. Application Data

(62) Division of application No. 18/183,088, filed on Mar. 13, 2023.

(57) **CLAIM**

The ornamental design for interactive phonics board set as shown and described.

DESCRIPTION

FIG. 1 is a front perspective view of an interactive phonics board set in a zipped state;

FIG. 2 is another front perspective view of the interactive phonics board set in an unzipped state;

FIG. 3 is a top perspective view of the interactive phonics board set with additional environment omitted and in an unzipped and partially open state;

FIG. 4 is a front elevation view of the interactive phonics board set in a flat state;

FIG. 5 is a rear elevation view thereof;

FIG. 6 is a left side elevational view thereof;

FIG. 7 is a right side elevational view thereof; and,

FIG. 8 is a top plan view thereof, the bottom plan view being a mirror image thereof.

The broken lines are directed to environment and form no part of the claimed design.

1 Claim, 6 Drawing Sheets
